UNITED STATES PATENT OFFICE.

HENRY LYNCH, OF LIDGERWOOD, NORTH DAKOTA.

WIRE-FENCE TOOL.

1,044,551.

Specification of Letters Patent. Patented Nov. 19, 1912.

Application filed February 18, 1910. Serial No. 544,561.

To all whom it may concern:

Be it known that I, HENRY LYNCH, a citizen of the United States, residing at Lidgerwood, in the county of Richland and State 5 of North Dakota, have invented certain new and useful Improvements in Wire-Fence Tools, of which the following is a specification.

This invention relates to improvements in 10 wire fence tools, and more particularly to a tool adapted to repair broken wires in fences and at the same time take up slack in the wire being repaired.

The object of my invention is to provide 15 a tool of this character that is simple in construction and cheap of manufacture adapted to unite the ends of broken wire; also to take up slack in wires not broken by forming kinks therein.

20 The invention consists of a tool made of a single piece of steel, having at one end an angular tapering tang, and at the other end a cylindrical coiling mandrel having an open longitudinal slot approximately its entire length, whereby a wire with a free end, or any continuous length of wire, may be 25 readily engaged and wound or coiled on the mandrel to form coils which may be then wound upon the straight portion of the wire 30 in a fence.

By providing a long open-ended slot in a coiling mandrel the end of a wire, which 35 may be bent, may be more readily engaged than it could be by a tool having a transverse hole, in which the end of a wire must be inserted; also a continuous slack wire 40 may be engaged for winding on the coiling mandrel, as could not be done with a tool having only a transverse aperture as here- 45 tofore proposed.

In the drawings forming a part of this specification, in which like characters of reference indicate corresponding parts in the several views; Figure 1 is an elevation of 50 my improved fence tool. Fig. 2 is a perspective view of the tool as in use, repairing a broken wire, in connection with an ordinary chest-brace. Fig. 3 shows the wires united. Fig. 4 is an elevation of another 55 form of fence tool.

Referring to the drawings, the end 1 of my fence tool is made square and tapering, similar to the end of the usual bit that is adapted to be used with an ordinary brace. 55 The other end of the tool is made with a cylindrical coiling mandrel 2 rounded off or

pointed at the extremity. The said coiling mandrel is of equal diameter for a suitable distance, approximately two inches, and has formed therein an open longitudinal slot 3, 60 which extends nearly its entire length. The intermediate portion 4, of the tool is cylindrical in form and reduced in size as compared with the slotted mandrel.

In operation my tool is intended to be used 65 in connection with an ordinary chest-brace A and in mending a broken wire the operation is as follows: In one end of the wire a loop *x* is formed, by any suitable means, large enough to receive the other end of the 70 wire *y* to be mended, which is passed through said loop and its end placed in the outer end of slot 3 in the coiling mandrel 2 and the mandrel is then made to bear on the loop *x*. The handle of the brace is held in 75 the left hand of the operator, the crank portion rotated with the right hand in the usual manner, and the slack wire *y* drawn through the loop and wound around the slotted part of the mandrel, forming a coil *z* until all the 80 slack is taken up, the tool being held in such a position on the loop *x* as to cause the tension brought to bear upon the wire *y* being wound thereon to be transmitted to the looped portion *x* as indicated in Fig. 2. The 85 tool is then, preferably, removed from the brace and passed around the straight part of the wire *y*, the coil *z* being bent back adjacent to the loop on wire *y*, at the same time gradually unwinding the coil from around 90 the tool and winding it upon the straight part *y*, Fig. 3, to prevent its withdrawal from the loop.

If there is not sufficient lap to the ends of the broken wires to be brought together, 95 the tool can be connected with one of the wires and operated to draw up the slack, which is removed from the tool, and the operation then carried out as previously described. It will be seen that in mending a 100 wire by this method the slack is taken up on both sides of the break and the wires made taut all along the line, or at least for a considerable distance.

In taking up slack in unbroken wires, the 105 wire at any point is placed in the slot of the tool, and the crank of the brace operated in the usual manner, which operation winds the wire in double strands around the mandrel. When the slack is taken up the tool 110 is twisted around the straight portion of the wire several times, to lock the kink or coil

- upon it in order to prevent the coil from unwinding, and the tool is then withdrawn.
- Another method of using my invention in joining the broken ends of wire is as follows: The ends are brought together so as to overlap at least two or three inches, which overlapped portions are inserted in the slot of the tool, and the projecting ends are then bent around the mandrel to prevent their withdrawal, and the tool rotated in the usual manner. The slack is thus wound around the mandrel from both directions at the same time. When the wire is sufficiently tight the tool is twisted around the straight portions of wire several times, thereby winding the coil around the same to lock the kink and prevent its becoming loose, and the tool is then withdrawn from connection with the wire.
- Fig. 4 illustrates another form of my invention, in which the inner end of the mandrel 2 is provided with a circumferential flange 5, having a vertical face toward the slotted end and tapering toward the opposite end. The purpose of this flange is to keep the wire being wound on the mandrel from sliding back on the part 4 of the tool. A further variation consists in making the slot 3, with walls converging toward the center of the mandrel to approximately a point at its inner end, and having formed therein transverse teeth 6, extending the entire length of the slot, which teeth tend to prevent the wire slipping from the slot.
- In winding the wire on the coiling mandrel, the end being engaged in the slot, the coiled part crosses the slot and forces the two halves of the mandrel into contact with said end in the slot, thereby tightly gripping and holding the same, as in a vise. The slot with rearwardly converging walls, Fig. 4, provides for engaging wires of different gage, and the transverse teeth better hold the engaged wire from slipping sideways. Evidently an open-ended longitudinal slot in the coiling mandrel has an advantage over a transverse aperture, heretofore proposed in this class of tools, inasmuch as it permits a wire, which may be bent or kinked at the end, to be readily engaged, as could not be done with a tool having only a transverse aperture, into which the end of a wire must be inserted. A continuous slack wire may also be readily engaged in the open-ended slot for winding on the coiling mandrel to take up the slack, which operation would be impossible with the above mentioned apertured tool.
- I claim as my invention and desire to secure by Letters Patent of the United States:
- A wire fence tool having at one end an angular and tapering tang, and at the other end a cylindrical coiling mandrel flanged at its inner end and having a longitudinal open toothed slot with walls converging toward the center and inner end thereof, substantially as described.
- In testimony whereof I affix my signature in presence of two witnesses.
- HENRY LYNCH.
